TROUSERS

Alfons Blankenhorn, Zurich, Switzerland

Application December 2, 1938, Serial No. 243,582
In Switzerland February 22, 1938

1 Claim. (Cl. 2—237)

My invention relates to trousers and has for its object the means for adjusting the fit of the waist of trousers.

Reference is to be had to the accompanying drawing in which

Fig. 1 shows a closed waistband. One part of the waistband is used as a pulling part.

Fig. 2 shows the shortened circumference of the arrangement of Fig. 1.

Fig. 3 shows the finished arrangement of the 10 waistband and the trousers.

Fig. 4 shows a perspective view of the waistband and the trousers.

Fig. 5 shows a loop with rollers.

The Figs. 1 and 2 show the principle of the construction of the patent application and the Figs. 3-5 show the finish. The scales of the different figures are different and they show only the scheme. The closed waistband consists of the part 19 and the foldings 15, 16. The roller 24 is fastened to the loop 17 which is fixed to the point 29 of the waistband 19. The rollers 22, 23 are fastened to the loop 21 and the buckle 20 with the pulling strap 18 is fixed to the point 30 and the pulling strap 18 is placed around the roller 22. The buckle 20 keeps always its position in relation to the point 30, which is fixed to the rear part 26 of the trousers.

If the arrangement of Fig. 1 is used by a person and it fits around the waist, all parts are tight. In case the waist of the man is smaller, the strap 18 has to be changed in the way Fig. 2 shows. The pulling strap 18 has changed its position in relation to the buckle 20 and the dis- 35

tance between the roller 22 and the buckle 20 is changed.

All parts are tight again. The part 14 is called the pulling part. If the distance between the point 30 and the roller 22 is shortened by the strap 18, the distance between the point 29 and the roller 23 is shortened too but the shortening is less than between the roller 22 and point 30. The buckle rests against the part 14 and is prevented from resting against the underwear.

The foldings 15, 16 are placed into the inside of the front part 25 of the trousers while the point 30 and the loop 21 are placed into the back part 26. The loop 21 is visible from outside. The arrangement of the pulling part 14 is shown in Figs. 1, 2 and all parts of the waistband have to be placed around the waist in a good tight fit. By fixing the loop 17 to the point 29 and by fixing the buckle 20 with the strap 18 to the point 30 of the waistband the trousers are finished. For loosening or tightening the waistband, the strap 18 has to be regulated by the buckle 20. The rollers 22 and 23 are covered with rubber.

Having described my invention what I claim as new and desire to secure by Letters Patent is:

Trousers having a waistband thereon, said waistband including a folded part having two folds, the folds being connected together and fitted with slidable attachments, one slidable attachment being fixed to the waistband, and a pulling device secured to the other attachment for the purpose of effecting adjustment of the waistband.

ALFONS BLANKENHORN.
